DESIGN FOR A FINGER RING

Ernest Hammer, Irvington, N. J.

Application June 7, 1940, Serial No. 92,882

Term of patent 3½ years

To all whom it may concern:

Be it known that I, Ernest Hammer, a citizen of the United States and a resident of Irvington, in the county of Essex and State of New Jersey, have invented a new, original, and ornamental Design for a Finger Ring, of which the following is a specification, reference being had to the accompanying drawing forming part thereof.

Figure 1 is a top plan view of a finger ring showing my new design.

Figure 2 is a front elevational view of the ring.
Figure 3 is a rear elevational view of the ring.
Figure 4 is a side elevational view of the ring, and

Figure 5 is an elevational view of the side of the ring opposite that shown in Figure 4.

I claim:

The ornamental design for a finger ring, as shown.

ERNEST HAMMER.
